(57) CLAIM

An ornamental design for a shower surround, as shown and described.

DESCRIPTION

FIG. 1 is a perspective view of the shower surround showing our new design;

FIG. 2 is a front elevational view thereof;

FIG. 3 is a top plan view thereof;

FIG. 4 is a right side view thereof; and,

FIG. 5 is a left side view thereof.

The broken lines showing of the shower base and drain is for illustrative purposes only and forms no part of the claimed design.
